UNITED STATES PATENT OFFICE.

CLAUDE W. ATKINSON, OF LITTLE HAMPDEN, GREAT MISSENDEN, ENGLAND.

PIANO-PLAYING MECHANISM AND THE LIKE.

1,068,399.

Specification of Letters Patent.

Patented July 22, 1913.

Application filed July 29, 1911. Serial No. 641,258.

To all whom it may concern:

Be it known that I, CLAUDE WILLIAM ATKINSON, subject of the King of Great Britain and Ireland, residing at Little Hampden, Great Missenden, in the county of Bucks, England, have invented new and useful Improvements in and Relating to Piano-Playing Mechanism and the Like, of which the following is a specification.

10 This invention relates to piano playing mechanism and the like particularly of the type described and illustrated in a sister application and has for its object the arrangement and construction of a vacuum chest of sheet metal of simple character and low cost which can be installed so as not to interfere with the knee room on an ordinary piano when in position as a part of a piano playing mechanism.

15 20 Figure 1 is a perspective view of the vacuum chest of stepped formation, and air trunks leading from the same to the orifices communicating with the playing table. Fig. 2 is a detail plan view of the end and front air trunks, showing the means of connection one to the other. Fig. 3 is a sectional view of the front air trunk taken on the line 3—3 of Fig. 2. Fig. 4 shows a part side elevation of an end trunk, showing the socket on 25 which the front air trunks are mounted. Fig. 5 shows a side view of one of the supporting devices within the stepped vacuum chamber, for supporting the walls of the same, and affording fastening means for the 30 power pneumatics. Fig. 6 is a part front elevation of the two front air trunks, showing the connecting means by which communication is made with the playing table. Fig. 7 is a plan of the same. Fig. 8 is a 35 40 sectional elevation of the key bed of an ordinary piano, showing a playing action having my improved form of vacuum chest embodied therein.

To carry the invention into effect the vacuum chest *a* is made of sheet metal in two parts *b* and *c*, bent up in the particular form shown in the drawings so as to form horizontal walls or ledges *d* and *e* on the part *b* and walls or ledges *d*¹ and *e*¹ on the part *c* corresponding in vertical position with the ledges *d* and *e* respectively.

Within the body of the vacuum chest *a* are arranged at intervals struts *f* adapted to support the part *c* wholly and to assist 50 in supporting the ledges *d* and *e* of the portion *b*. These struts further form a part of

the detachable means for holding the pneumatics in position.

Referring now to Fig. 1 the vacuum chest *a* is connected at its end with side trunks *g*, 60 which at the front portion of the mechanism are connected to a long trunk *h*, arranged from side to side and two short trunks *i*, which extend up to the front plate *j* to which the playing table is attached. 65 This trunk *h* has a horizontal wall *h*¹ at the top and a vertical wall *h*² at the front side which is in the same plane as the front wall *i*¹ of the trunk *i*.

It will be noticed that the trunks *h* and *i* 70 are arranged so that the long axis of the section of one trunk is at right angles to the similar axis of the other trunk, in order to form a girder of great constructural rigidity on the one hand and a proper transverse sectional area of passage on the other.

The air trunk connections *h* to an externally disposed playing table of any suitable construction such, for example, as that described in my U. S. Patent #1,000,359, are 80 disposed on the front face of the combined trunks *h* and *i*, and in order to form a simple and effective connection between the trunks *g* and *h* and *i* I provide as shown in Figs. 2, 3 and 4 a raised shoulder *l* surrounding an orifice *l'* in the wall of the trunk *g*, over which shoulder the trunks *h* and *i* pass as a sleeve, the walls *h*¹ and *h*² of the trunk *h* being disposed along the sides *l*² and *l*³ respectively of the shoulder *l*. 85 90 Blocks *m* are inserted and held in the trunks *h* and *i* into which screwed studs *n* provided with nuts *o* are inserted so as to draw the trunks *h* and *i* respectively, into close proximity to the trunks *g*.

Dished caps *p* are attached to the ends of the trunks *g* in order to close the same. The trunk *h* is divided at its central part by stop pieces *q* formed of a length of tube of rectangular section and of such a depth and length as to completely block up the said trunk when placed therein with its axis at right angles to the axis of the trunk (see Fig. 6) which not only divide the trunk into bass and treble sections but at the same time stiffens up the trunk walls locally so as to enable the riveted connections between the two trunks *h* and *i* to be made in a substantial manner.

The ends of the tracker pipes are inserted 110 into rearwardly dished holes *r* (Fig. 8) stamped in the front perforated plate *j* to

form a flange and are locked in position by being expanded into the holes formed by the flanged portion. This application is a division of applicant's co-pending application #554346, filed April 9th, 1910.

Having thus fully described my invention, I claim as new and desire to secure by Letters Patent:—

1. In a piano playing mechanism of the type described, a vacuum chest of sheet metal consisting, in combination, of two main parts, one part *b* forming the main body and having one horizontal lower wall, two upstanding vertical walls and two horizontal upper walls *d* and *e* in different planes and having depending flanges all formed integrally from one sheet of metal, and another part *c* independent of the first part *b* having two horizontal steps *d*¹ and *e*¹ corresponding in vertical disposition with the walls *d* and *e* respectively, each step having a depending flange and struts of skeleton structure arranged at intervals vertically along the length of the vacuum chest and between the parts *b* and *c* and proportioned and positioned to support the said independent stepped part *c* in its proper relative position with the part *b*, substantially as described.
2. In a piano playing mechanism of the type described, the combination of a key

bed of a piano, a vacuum chest arranged along the back of the underside of the key bed, lateral trunk pipes connected with the ends of the vacuum chest, front trunk pipes connected to the said lateral trunks, a playing table externally disposed relative to the piano case and means of hollow connection between each front trunk pipe and the said playing table, substantially as described.

3. In a piano playing mechanism of the type described, the combination of a key bed of a piano, a vacuum chest arranged along the back of the underside of the key bed with two lateral trunk pipes connected with the ends of the vacuum chest, a compound front trunk pipe consisting of a transverse trunk pipe from one lateral trunk pipe to the other forming a girder, two subsidiary trunk pipes disposed under the transverse trunk pipe, a playing table externally disposed to the piano case and connecting means between the said compound trunk pipe and the said playing table, substantially as described.

In testimony whereof I have signed my name to this specification in the presence of two subscribing witnesses.

CLAUDE W. ATKINSON.
